United States Patent

Des. 239,136
Patented Mar. 9, 1976

239,136

BINOCULARS

Erwin Altenheiner, Hasselborn, and Joachim Hornschu,
Oberkochen, Germany, assignors to Carl Zeiss-Stiftung,
Oberkochen, Germany

Continuation of abandoned design applications Ser. No.
427,411 and Ser. No. 427,416, Dec. 21, 1973. This ap-
plication July 9, 1974, Ser. No. 486,881.

Claims priority, application Germany June 25, 1973

Term of patent 14 years

Int. Cl. D16—06

U.S. Cl. D57—1 E

FIG.2

FIG.4

FIG.1

FIG.5

FIG.3

FIG. 7

FIG. 9

FIG. 6

FIG. 10

FIG. 8

FIG. 1 is a front elevational of binoculars in open position, showing our new design;

FIG. 2 is a top plan view thereof;

FIG. 3 is a front elevation of binoculars in closed position;

FIG. 4 is a top plan view thereof;

FIG. 5 is a side elevation thereof;

FIG. 6 is a front elevation of a modified form of binoculars in open position;

FIG. 7 is a top plan view thereof;

FIG. 8 is a front elevation of the modified form of binoculars in closed position;

FIG. 9 is a top plan view thereof; and

FIG. 10 is a side elevation thereof.

This is a continuation of design applications Ser. No. 427,411 filed Dec. 21, 1973 and Ser. No. 427,416 filed Dec. 21, 1973 and now both abandoned.

We claim:

The ornamental design for binoculars, as shown and described.
